(57) **CLAIM**

I claim the ornamental design for a platform rack, as shown and described.

DESCRIPTION

FIG. 1 is a top, front, and right perspective view of a platform rack showing my new design;

FIG. 2 is a front elevational view thereof, the rear being a mirror image;

FIG. 3 is a left side elevational view thereof, the right side being a mirror image;

FIG. 4 is a top plan view thereof; and,

FIG. 5 is a bottom plan view thereof.

1 Claim, 4 Drawing Sheets

FIG. 1

FIG. 2

FIG. 3

FIG. 4

FIG. 5
